LAPPING ARM

Herbert S. Indge, Westboro, Mass., assignor to
Norton Company, Worcester, Mass., a corpora-
tion of Massachusetts

Application June 16, 1949, Serial No. 99,375

6 Claims. (Cl. 51—204)

1

The invention relates to lapping machines and more particularly to an improved lapping apparatus for lapping cylindrical surfaces such as crank pins and the like.

One object of the invention is to provide a simple and thoroughly practical crankshaft lapping machine. Another object of the invention is to provide an improved lapping arm. Another object is to provide a lapping arm having a plurality of self-aligning lapping elements. A further object of the invention is to provide a lapping arm having a plurality of lapping elements each of which may be precisely adjusted by means of a nut and screw mechanism. A further object of the invention is to provide a compound screw adjustment for the lapping elements of a crankshaft lapping machine. Another object of the invention is to provide a lapping arm having a plurality of lapping elements with precision screw adjusting mechanisms whereby the lapping element or elements may be adjusted to compensate for taper on a work piece.

A further object of the invention is to provide an improved lapping arm construction which may be applied to a lapping machine such as, for example, that shown in my prior U. S. Patent No. 2,166,009, dated July 11, 1939. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a side elevation of the improved lapping arm together with the supporting mechanism therefor;

Fig. 2 is a fragmentary side elevation, on an enlarged scale, having parts broken away and shown in section to illustrate the mechanism for supporting and adjusting the lapping elements, with the lapping elements in engagement with a work piece;

Fig. 3 is a similar fragmentary side elevation, on an enlarged scale, with the lapping elements and associated parts in an inoperative position;

Fig. 4 is a cross sectional view, on an enlarged scale, taken approximately on the line 4—4 of Fig. 3, showing the adjusting mechanism and self-aligning mounting for one of the lapping elements;

2

Fig. 5 is a fragmentary sectional view, on an enlarged scale, taken approximately on the line 5—5 of Fig. 4, showing the details of the lap adjusting mechanism and the self-aligning mounting therefor; and

Fig. 6 is a cross sectional view, on an enlarged scale, taken approximately on the line 6—6 of Fig. 3, showing the adjusting mechanism and the self-aligning mounting for one of the lapping elements.

A crankshaft lapping machine of the type shown in my prior U. S. Patent No. 2,166,009 is provided with a pair of parallel lapping arm supporting rods or slides 10 and 11 which serve as supports for a plurality of lapping arm supporting members 12, only one of which has been illustrated in the present drawings. The supporting member 12 is provided with a lower half 13 which is clamped to the member 12 by means of 15 clamping screws 14 and 15. The supporting member 12 and lower half 13 are each formed with surfaces which mate with the supporting rods or slides 10 and 11. It will be readily apparent from the foregoing disclosure that by 20 loosening the clamping screws 14 and 15 (Fig. 1), the supporting member 12 may be adjusted longitudinally relative to the supporting rods or slides 10 and 11 to align the lapping mechanism with the work piece to be lapped. After the supporting member 12 has been initially adjusted, it may be clamped in adjusted position by tightening the clamping screws 14 and 15.

The lapping arm supporting member 12 serves as a support for a pivotally mounted arm 16. 35 A pivotal connection 17 is provided between the supporting member 12 and the pivotally mounted arm 16. A lapping arm 18 is pivotally connected by a pivotal connection 19 to the upper end of the arm 16. It will be readily apparent from the foregoing disclosure that the arm 18 is free to swing on the pivotal connection 19 and is free to move longitudinally by swinging the arm 16 on the pivotal support 17.

The lapping arm 18 comprises a pair of parallel 45 side plates which are spaced apart by a plurality of spacing blocks 20, 21, 22, 23 at one end and by a bracket 24 at the other end which is connected to the pivotal connection 19. The lapping arm 18 serves as a support for a pair of spaced 50 pivotally mounted levers 25 and 26 which are pivotally connected by studs 27 and 28, respectively, with the lapping arm 18. The lever 25 serves as a support for a pair of spaced lap holders 29 and 30 which support arcuate-shaped lapping elements 31 and 32, respectively. The

lapping elements 31 and 32 may be metallic elements such as for example cast iron in which case a lapping compound is fed to the work and lapping elements in a manner to be hereinafter described. If desired however the lapping elements 31 and 32 may be made of bonded abrasive material such as aluminum oxide, silicon carbide or diamond bonded by any of the well known standard bonding mediums.

A precision adjusting mechanism is provided for adjusting the lapping elements 31 and 32 relative to the work piece being lapped. These mechanisms are preferably compound screw mechanisms whereby a relatively coarse right and left hand thread may be utilized to obtain a relatively fine feeding movement of the lapping elements. As illustrated in the drawings a pair of adjusting screws 33 and 34 may be formed with a $\frac{3}{4}$ -16 R. H. thread which mates with correspondingly threaded apertures in the lever 25. The screws 33 and 34 are provided with threaded apertures which may be provided with for example a $\frac{7}{16}$ -20 L. H. thread. A screw 37 is provided having a L. H. thread to mate with the L. H. threaded aperture 36. It will be readily apparent from the foregoing disclosure that by rotation of the screws 33 and 34 relative to the lever 25 and to the screw 37, a relatively fine feeding adjustment of the lap holders 29 and 30 may be obtained.

It is desirable that the lapping elements 31 and 32 be provided with a self-aligning mounting so that the lapping elements may readily align themselves with the peripheral surface of the work to be lapped. The screw 37 is provided with a spherically-shaped end 38 which mates with a partial internal spherical surface 39 formed adjacent to one end of an elongated aperture 40 (Fig. 4). It will be readily apparent that the lap holder 29 may rock on the spherical end 38 of the screw 37 to align the operative surface of the lapping element 31 with the work piece to be lapped.

It is desirable to provide a suitable mechanism for detachably holding the lap holder 29 on the spherical end 38 of the screw 37. This mechanism may comprise a diametrically arranged hole 41 formed in the spherical end 38. The lap holder 29 is provided with a pair of opposed aligned spring pressed detents 42 and 43 which are arranged to engage with the opposite ends of the hole 41. It will be readily apparent that due to the spring pressed detents 42 and 43, the lap holder 29 will be free to rock in a plane normal to the axis of the work piece being lapped to align the operative surface of the lapping element 31 with the surface being lapped. The detents 42 and 43 also serve to detachably hold a lap holder 29 and the lapping element 31 in supporting engagement with the lever 25.

The adjusting screw 34 is similarly provided with a R. H. thread 44 which mates with a correspondingly threaded aperture in the lever 25. The screw 34 is provided with a L. H. threaded aperture 45 which engages or meshes with a L. H. screw 46. The screw 46 is provided with a spherically shaped end 47 which mates with a partial spherical surface 48 formed in the lap holder 30. The spherical end 47 is provided with a diametrically arranged hole 49. The lap holder 30 is provided with a pair of spaced aligned spring pressed detents 50 and 51 by means of which the lap holder 30 and the arcuate-shaped lapping element 32 may be detachably supported on the spherical end 47 of the screw 46 and due to the

spherical support thereof, the lapping element 32 will align itself with the surface of the work piece to be lapped when moved to an operative position.

- 5 The lapping elements 31 and 32 are provided with arcuate-shaped lapping surfaces 52 and 53 which are shaped to correspond with the surface on the work piece to be lapped. In order to facilitate a precise adjustment of the lapping elements 31 and 32, the heads of the adjusting screws 33 and 34 are serrated. A pair of spring latches 55 and 56 are fixedly mounted on the lever 25 and are arranged to engage the serrations in the heads of the screws 33 and 34 respectively to hold the screws 33 and 34 in adjusted position. The springs 55 and 56 have sufficient spring pressure to maintain the screws in adjusted position but are such that a manual adjustment of the screws is readily obtained.
- 10 In the lapping of relatively large diameter cylindrical work pieces, it is desirable to provide a suitable adjustment for the lapping element so that compensation may be made to correct a tapered condition on the surface of the work piece being lapped. This is preferably accomplished by providing a second pair of screws which are arranged parallel to the adjusting screws 33 and 34, only one of which has been illustrated in Fig. 4 of the drawings. As illustrated in Fig. 4, an adjusting screw 33a is provided having a R. H. thread 35a which mates with a R. H. threaded aperture in the lever 25 which is parallel to the threaded aperture supporting the screw 35. The screw 35a is provided with an internally L. H. threaded aperture 36a which meshes with or engages a L. H. screw 37a. The L. H. screw 37a is provided at its right hand end (Fig. 4) with a spherical end 38a which mates with a partial internal spherical surface 39a formed in the elongated aperture 40. The spherical end 38a is similarly provided with a diametrically arranged hole 41a which serves with a pair of spring pressed detents (not shown) to provide a self-aligning movement of the lap holder 29 and also to facilitate removal of the lap holder 29 when desired. It will be readily apparent from the foregoing disclosure that by manipulation of the screws 33 and 33a, the lapping element 31 may be adjusted relative to the axis of the work piece being lapped so as to compensate or correct for any tapered condition on the peripheral surface thereof. A similar parallel screw adjustment is provided for the lap holder 30. This construction is identical with that just described and consequently has not been illustrated and described in detail. An adjusting screw mechanism arranged parallel to the adjusting screw 34 is provided to facilitate adjustment of the lapping element 32 to compensate for taper on the work piece.
- 15 The adjusting screws 33 and 33a and also the adjusting screws 34 and the adjusting screw parallel thereto are preferably arranged so that when the lapping elements 31 and 32 are in operative engagement with the peripheral surface of the work piece 54 to be lapped, the adjustment thereof will in each case be in a radial plane passing through the axis of the work piece 54. As previously described both of the lapping elements 31 and 32 are arranged with self-aligning mountings so that they may rock about axes which are substantially parallel with the axis of the work being lapped. The lapping elements 31 and 32 may be adjusted independently to correct for any tapered condition on the work piece

to be lapped so that a true cylindrical surface will be produced on the periphery of the work piece 54.

A lap holder 60 which supports an arcuate-shaped lapping element 61 is adjustably mounted on the lever 26. The lap holder 60 is provided with a dovetailed slideway 62 which mates with a dovetailed slide 63 formed on a supporting block 64 (Fig. 6). The supporting block 64 is mounted on the left hand end of a stud 65 and is supported between a head 66 formed integral with the stud 65 and a nut 67 threaded thereon. The stud 65 is provided with an integral L. H. screw 68 which mates with a L. H. threaded aperture 69 formed within a R. H. screw 70. The screw 70 mates with or meshes with a threaded aperture extending through the lever 26. The screw 70 is provided with a serrated head or knob 71. The lever 26 supports a spring latch 72 which is arranged to engage the serrations formed on the head 71 to maintain the screw 70 in adjusted position.

The dovetailed slideway 62 and the dovetailed slide 63 are loosely fitted so that the lap holder 60 and the lapping element 61 are free to move in a tangential direction relative to the peripheral surface of the work piece 54 being lapped to align the arcuate surface 73 of the lapping element 61 with the surface to be lapped. In order to limit the aligning movement of the lap holder 60, a stud 95 is supported by the lever 26 (Fig. 2) and is held in adjusted position thereon by means of a clamping screw 96. The stud 95 projects into clearance holes 97 and 98 formed in the supporting blocks 64 and the lap holder 60 respectively. It will be readily apparent from the foregoing disclosure that a tangential aligning movement of the lap holder 60 may be had in either direction as limited by the clearance between the stud 75 and the clearance holes 77 and 78 previously described. It will be readily apparent from the foregoing disclosure that the lapping elements 31 and 32 are free to rock when moved into operative engagement with the periphery of the work piece 54 to be lapped to align themselves with the peripheral surface thereof and the lapping element 61 is free to slide in a tangential direction relative to the peripheral surface of the work piece 54 to align the lapping element 61 with the surface thereof.

A suitable manually operable mechanism is provided for moving the levers 25 and 26 together with the lapping elements 31 and 32 and 61 respectively to and from an operative position. This mechanism may comprise a pair of toggle levers 75 and 76 having their opposite ends pivotally connected by studs 77 and 78 respectively with the levers 25 and 26 respectively. The inner ends of the toggle levers 75 and 76 are pivotally connected to a common pivot stud 79 which is arranged to slide within elongated slots 80 formed in the side plates of the lapping arm 18. To facilitate actuation of the toggle levers 75 and 76, a manually operable bell crank lever 81 is pivotally supported on a stud 82 carried by the lapping arm 18. The bell crank lever 81 is provided with a downwardly extending arm 83 which is connected by means of a pivot stud 84 with one end of a link 85. The other end of the link 85 is pivotally connected with the stud 79.

A tension spring 86 is connected between the link 85 and a stud 87 carried by the lapping arm 18 and serves normally to hold the parts in an

operative position as illustrated in Figs. 1 and 2. When it is desired to open the lapping elements after a lapping operation has been completed, the bell crank lever 81 is rocked in a clockwise direction (Figs. 1 and 2). This movement rocks the arm 83 also in a clockwise direction to move the link 85 toward the left (Figs. 1 and 2) so that the pivot stud 79 slides within the elongated slot 80 into the extreme left hand end thereof. This movement of the stud 79 serves to shift the toggle levers 75 and 76 from a locked position as illustrated in Figs. 1 and 2 into the position as illustrated in Fig. 3 thereby swinging the levers 25 and 26 about their supporting pivots 27 and 28 so as to move the lapping elements 31-32 and 61 to inoperative positions out of engagement with the peripheral surface of the work piece 54.

Similarly when it is desired to move the lapping elements to an operative position, the bell crank lever 81 may be moved from the position illustrated in Fig. 3 in a counter clockwise direction to shift the toggle levers 75 and 76 into the positions illustrated in Fig. 2, thereby swinging the levers 25 and 26 to move the lapping elements 31-32 and 61 into operative lapping engagement with the periphery of the work piece 54. Due to the action of the toggle levers 75 and 76, the lapping elements are non-yieldably held in an operative position.

In case metallic lapping elements are utilized, a suitable reservoir 90 may be provided for containing a supply of lapping compound which may be fed by means of the wick 91 through a tube 93 and the wick 94 onto the peripheral surface of the work piece being lapped. The reservoir 90 is provided with a cover plate 92 to facilitate filling the reservoir 90 with the desired fluid or semi-fluid lapping compound.

The operation of this improved lapping arm will be readily apparent from the foregoing disclosure. A work piece to be lapped is positioned in the machine after which the toggle lever 81 is shifted to move the lapping elements 31-32 and 61 into operative lapping engagement with the peripheral surface of the work piece 54. Due to the self-aligning mountings, the arcuate lapping surfaces 52-53 and 73 will align themselves with the surface to be lapped. By adjustment of the screw mechanisms above described, the lapping elements 31-32 and 61 may be adjusted toward and from the work periphery to provide the desired lapping pressure between the lapping elements and the work surface being lapped. As previously explained the lapping elements 31 and 32 may be adjusted so as to compensate for taper on the work piece to lap a predetermined taper thereon or if desired may be adjusted to produce a predetermined tapered surface on the work. It will be readily apparent that by providing interchangeable lap holders 29, 30 and 60, various diameters of work may be lapped by merely interchanging the lap holders and lapping elements attached thereto.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a crankshaft lapping machine having a pivotally mounted lapping arm, a pair of pivotally mounted spaced lap-supporting levers on said arm, a toggle lever mechanism to move said levers to and from an operative position, an arcuate lapping element supported on one of said levers, a pair of spaced parallel adjusting screws on said lever to support said lapping element and to facilitate precise adjustment thereof, the axes of said screws lying in a plane passing through the work axis when the lapping element is in an operative position to facilitate adjustment of said lapping element to compensate for taper on the work piece, an arcuate lapping element on the other lever, and means including a radially extending adjusting screw to facilitate precise adjustment of the latter element.

2. In a crankshaft lapping machine as claimed in claim 1, in combination with the parts and features therein specified, of a universal connection between said parallel adjusting screws and the first lapping element to facilitate self-alignment of said element relative to the surface of the work piece to be lapped, and a slideable connection between the second lapping element and its adjusting screw to facilitate a tangential self-alignment of said second element relative to the surface of the work to be lapped.

3. In a crankshaft lapping machine as claimed in claim 1, in combination with the parts and features therein specified, of a ball and socket connection between the parallel adjusting screws and the first lapping element to facilitate self-alignment of said element relative to the surface of the work piece to be lapped about an axis substantially parallel to the work axis, and a tangentially arranged slideway interposed between the second lapping element and its adjusting screw to facilitate a tangential self-alignment of the second element relative to the surface of the work piece to be lapped.

4. In a crankshaft lapping machine having a pivotally mounted lapping arm, a pair of pivotally mounted spaced lap supporting levers on said arm, a toggle lever mechanism to move said levers to and from an operative position, a self-aligning arcuate lapping element supported on one of said levers, a pair of spaced parallel compound ad-

justing screws on said lever to support said lapping element and to facilitate a precise adjustment of said element, an arcuate lapping element on the other lever, and means including a compound adjusting screw interposed between said latter lever and the second lapping element to facilitate a precise adjustment of said latter element.

5. In a crankshaft lapping machine having a pivotally mounted arm, a pair of spaced pivotally mounted toggle-actuated levers on said arm, a self-aligning arcuate-shaped lapping element on one of said levers, means including a pair of spaced radially extending adjusting screws on said lever which are arranged normal to the axis of the work piece to be lapped to facilitate adjustment of said lapping element to compensate for taper on the work piece, a radially adjustable member on the other lever, a dovetailed slideway on said member, an adjusting screw on said latter lever to facilitate a radial adjustment of said member, and an arcuate-shaped lapping element having a slideway mating with said dovetailed slideway, said dovetailed slideway being arranged to facilitate a self-aligning tangential adjustment of said latter element relative to the surface to be lapped.

6. In a crankshaft lapping machine having a movable crankpin lapping arm, a pair of spaced toggle-actuated levers pivotally mounted on said arm, a pair of spaced arcuate-shaped lapping elements on one of said levers, a pair of adjusting screws on said lever for precisely adjusting each of said elements, a ball and socket connection between each of said screws and the lapping element to provide a self-aligning movement of the element relative to the surface to be lapped, a tangentially arranged dovetailed slideway, an adjusting screw on the other arm to facilitate adjustment of said slideway in a substantially radial direction relative to the axis of the work piece being lapped, and an arcuate-shaped lapping element having a dovetailed slideway mating with said slide to facilitate a tangential self-aligning movement of the latter element relative to the surface of the work piece to be lapped.

HERBERT S. INDGE.
